CABLE OPERATED CURTAIN FIXTURE

Andrew T. Hagerty and Theron F. Brenneman,
Elkhart, Ind., assignors to The Adlake Company, Chicago, Ill., a corporation of Illinois

Application September 5, 1945, Serial No. 614,512

6 Claims. (Cl. 160—279)

1

Our invention has to do with improvements in cable curtain fixtures.

It is an object of the invention to provide an improved roller curtain installation, particularly adapted for use in a railway passenger car or an automobile bus, wherein the curtain is mounted in a window frame having opposite side guide channels which receive the ends of a hollow bottom fixture on the curtain, and, wherein the position of the bottom of the curtain is adjustably controlled by engagement with a pair of cables, each having one end secured to the window frame adjacent the top of one side guide channel and the other end secured to the frame adjacent the bottom of the opposite side guide channel, and each extending from its upper end downwardly along the adjacent guide channel, then through the hollow bottom curtain fixture, and down along the opposite guide channel to the other end.

More specifically, it is an object of our invention to provide, in the curtain construction described, improved means for controlling the positioning of the bottom of the curtain, which means may be adjusted to secure proper operation of the same after it has been installed.

Another object of our invention is to provide an anti-rattler means, to eliminate the noise usually present in such curtain constructions, due to initially loose fitting parts, or to parts having become loose through wear.

Further objects of our invention will be apparent from the illustrated preferred embodiment of the same which is shown, by way of example, in the accompanying drawings wherein:

Fig. 1 is an elevation of a curtain installation embodying our improvements;

Fig. 2 is a section on a larger scale, taken on line 2—2 of Fig. 1;

Fig. 3 is a detail view showing a top cable clip mounted in a side guide channel, taken on line 3—3 of Fig. 1;

Fig. 4 is a view taken on line 4—4 of Fig. 3;

Fig. 5 is a section through the bottom of the curtain to an enlarged scale;

Fig. 6 is a detail view showing a bottom cable anchor mounted in a side guide channel, taken on line 6—6 of Fig. 1;

Fig. 7 is a view taken on line 7—7 of Fig. 6;

Fig. 8 is a section taken on line 8—8 of Fig. 1;

Fig. 9 is a view taken on line 9—9 of Fig. 8, but to an enlarged scale;

Fig. 10 is a section taken on line 10—10 of Fig. 9;

2

Fig. 11 is a section taken on line 11—11 of Fig. 8;

Fig. 12 is an elevation of the anti-rattler member; and

Fig. 13 is a side view of the anti-rattler member.

A preferred form of our construction is shown, by way of example, in Fig. 1, installed in a window of a railway passenger car or automobile bus.

10 The curtain 10 is mounted in a window frame 11 which is secured in an aperture in the wall 12 of the vehicle body, and which comprises a bottom sill 13, a top header 14 and oppositely disposed side guide channels 15. A conventional sash unit 16 is supported on the outer side of the frame 11. The curtain 10 which is arranged to be raised and lowered adjacent the one side of the sash 16 is attached to the roller 17, Fig. 2, which is supported in the header 14 by the

20 brackets 18, in a conventional manner. The bottom or free end of the curtain has attached thereto an elongated fixture tube 19 which is adapted to receive two cables 20 and 21 by means of which the tube is retained in horizontal position as it moves up and down in positioning the bottom of the curtain. Each one of the cables 20 and 21 is attached to the frame adjacent the top of one of the side guide channels 15 and extends downwardly along the side guide channel

30 to the end of the tube 19, then through the tube to the opposite side of the window, and then down along the guide channel 15 at that side to a point of attachment adjacent the bottom of the channel. By this arrangement the bottom 35 of the curtain may be readily raised or lowered to any desired position and will be retained in such position by the frictional engagement with the cables with the tube.

Where the window in which the curtain is installed is relatively wide, which is frequently the case in passenger cars and busses, the tube 19 on the bottom of the curtain 10 is very apt to be grasped, by the person attempting to raise or lower the curtain, at some distance from the center, that is, near one side or the other of the window, so that force is applied near the end of the same which tends to tilt or twist the tube out of horizontal position and to bow the tube in a manner to pull the opposite end out of its position in its guide channel. To overcome this difficulty it is found desirable not only to have the tube ends move relatively freely in the side guide channels but also to have the cables properly adjusted with respect to the tube 19 and to each

40 other, so that the tube 19 will move freely yet 45 50 55

steadily on the cables. Therefore, it is desirable to be able to adjust the cables from time to time to take up stretch or wear and to maintain them in proper relation with respect to the tube 19 and to each other, so that the tube 19 will, at all times, be retained in horizontal position.

We have provided for this adjustment by means of a top cable clip 22 which is shown in detail in Figs. 3 and 4. The clip 22 is provided on one end with wing portions 23 which are bent over the end of the cable and permanently secured thereto, by brazing or the like. The other end or main portion of the clip 22, in the preferred construction, has an elongated aperture 24 adapted to receive a machine screw 25 by means of which the clip is secured in the guide channel 15. The position of the top end of each cable may thus be adjusted by movement of the clip 22 within the limits of the length of the aperture 24, which is made as long as desirable to provide for proper adjustment of the fixture rod 19 and to compensate for stretch and wear. The lower end of each cable is securely attached to the frame in the manner shown in Figs. 6 and 7. A bottom cable anchor member 26 is provided having a laterally projecting portion 27 in which there is an aperture 28 to receive the lower end of the cable, the cable being secured therein by the set screw 29. The member 26 is secured in the guide channel 15 by means of a set screw 30 which is received in an aperture 31 in the lower portion of the member. This arrangement provides a fixed anchorage for the lower end of each of the cables.

Referring to Fig. 5, the tube 19 is secured to the bottom of the curtain 10 by a securing strip 32 which is doubled back upon itself around the tube and secured by stitching 33 or the like to the bottom of the curtain 10. An apron member 34 which comprises two parts 35 and 36 is secured around the strip 32 by connecting the parts with spaced set screws 37. The apron 34 provides a grip for the user and also secures the tube 19 more firmly to the curtain 10. Other constructions may be adopted to securely fasten the tube 19 to the bottom of the curtain. The tube 19 extends the length of the curtain and has attached to each end a fixture tip 38, details of which are shown in Figs. 8 to 11. The fixture tip 38 has a screw-threaded connection 39 with the end of the tube 19 and extends into the channel 15. The tip 38 is flared outwardly toward the top and the bottom as shown at 40. It is also flattened on the sides so that the end is received within the confines of the channel 15. The outer end of the tip 38 is, of course, open to receive the cables 20 and 21 which pass through the tip into tube 19 in frictional engagement with the inside of the tip. The tip 38 is provided on each of its flattened sides with an aperture or indent 41. It also has a portion 42 cut away on each side at the outer end. An anti-rattler member 43 is provided as illustrated in Figs. 12 and 13. The anti-rattler member 43, which is made of rubber or some similar material, is provided with projecting side members 44 which are adapted to be received in the apertures 41 of the tip 38 to retain the member 43 in position in the tip. The member 43 also has extending side portions 45 which are received in the cut-away portion 42 of the tip 38 and project beyond the same.

The shape of the member 43 is such that when it is in position in the tip 38 there is sufficient clearance between the surface 46 of the member

and the opposed inner walls of the tip 38 to permit the passage of the cables 20 and 21. It will be obvious that by securing an anti-rattler member 43 in each of the tips 38 direct engagement of the tip with the channel 15 will be prevented and any engagement will be between the surfaces of the channel 15 and the projecting portions 45 of the member 43. This arrangement eliminates the rattling noise in operating the curtain which would otherwise result from engagement of the tips 38 with the channels 15. We have provided the tube 19 with an inner rubber tube 47 to further reduce the noise of operation by eliminating any noise which would otherwise result from the cables vibrating and striking against the inner walls of the tube.

As shown in Fig. 8 the channel 15 includes a light shielding flange 48 which extends inwardly from the channel guide 15 over the side edge of the window curtain 10. The arrangement of the channel 15, as shown in Fig. 8, is but one of many arrangements which might be adopted. It is necessary for proper operation of the curtain that the channel 15 include a guide portion 49 to receive the fixture tips on the ends of the tube 19 and guide them in their movement, which movement accompanies the raising and lowering of the bottom of the curtain.

While we have disclosed our construction as particularly adapted for use in a railway passenger car or automobile bus, it is not intended that its application be limited to such installations. The arrangement may be found useful in any installation where a retractable curtain or shade is employed to cover an opening and where it is desirable to be able to readily raise and lower the bottom of the curtain and have it remain in a selected position, particularly, where a wide opening is involved. Other details of construction within the spirit of our invention will be apparent to those skilled in the art.

We claim:

1. In window curtain construction of the type having a roller mounted curtain with a tube on the free end thereof, and vertical channels adapted to guide the ends of the tube, a pair of cables each of which is secured at its upper end in the upper portion of one of the channels and at its lower end in the lower portion of the opposite channel, the intermediate portions of said cables extending through said tube and the end portions thereof extending in opposite directions from the ends of the tube, a fixture tip on each end of said tube comprising a flattened, flared, open ended tubular section, adapted to freely slide in the adjacent guide channel, said fixture tip having curved internal cable bearing surfaces, and a removable, resilient anti-rattler member frictionally secured in the open end of said flared tubular section, said anti-rattler member having its inner portions spaced from said cable bearing surfaces and its outer portions extending laterally of the associated tubular section for engagement with the associated guide channel.

2. A window construction comprising a frame having guide channels along opposite sides, a roller curtain having its roller mounted adjacent one end of said guide channels and having a tubular rod member on its movable end, end extensions on said rod member having flattened flared open ends received in said guide channels, a pair of cables, each having one end attached adjacent the curtain roller mounting at the end of one of said guide channels and extending along said guide channel, through said tubular mem-

ber on the free end of the curtain, and along the opposite guide channel, and attached at the other end of the said opposite guide channel, an anti-rattler member removably positioned in the open end of each of said end extensions, the respective end extensions having cut away portions and said anti-rattler members having portions received therein and extending outwardly therefrom for engagement with the said guide channels.

3. In a roller curtain installation wherein the curtain is mounted in a window frame having opposite side guide channels which receive the ends of a hollow bottom fixture on the curtain, and wherein the position of the bottom of the curtain is adjustably controlled by engagement with a pair of cables, each cable having one end secured to the window frame adjacent the top of one of said guide channels and the other end secured to the frame adjacent the bottom of the opposite side guide channel with an intermediate portion extending through the hollow bottom curtain fixture; an anchor member for securing an end of one of the cables in adjusted relation to the window frame comprising a plate-like member positioned in the associated side guide channel and having means for securing the same in adjusted relation to the frame and a member projecting outwardly of the side guide channel and having means for rigidly securing thereto the other end of the cable.

4. In a cable curtain fixture comprising a tubular cable receiving member adapted for association with the end of a curtain, flattened open ends on said tubular member having oppositely directed internal cable bearing surfaces and free end portions adapted to be received in guide channels of a window frame and anti-rattler members having portions frictionally retained in said open ends and other portions extending beyond the flattened sides of said open ends adapted for engagement with said guide channels, said frictionally retained portions being in spaced relation to said cable bearing surfaces.

5. In a cable curtain fixture comprising a tubular cable receiving member adapted for association with the end of a curtain, open end members on said tubular member having relatively flat side face portions and free end por-

tions adapted to be received in freely sliding relation in the guide channels of a window frame, said open end members having oppositely directed internal cable bearing surfaces, and anti-rattler members having portions extending into and retained in the free ends of said open end members and having other portions extending beyond the flat side face portions of said open end members adapted for engagement with said guide channels, said portions of said anti-rattler members which extend into said open end members being in spaced relation to said cable bearing surfaces.

6. In a cable curtain fixture which is attachable to the lower end of a window curtain for coaction with cables and vertical guide channels at the sides of a window, a tubular member through which overlapped portions of the cables at the sides of the window are extendable horizontally, said member being provided adjacent its ends with vertically spaced upwardly and downwardly curved cable bearing surfaces about which the cables entering the ends of said member are trained, and said member being also provided beyond said curved bearing surfaces with extensions, which extensions include cable guiding portions which close off the space beyond said bearing surfaces outwardly of the latter to confine the cables to said surfaces, and also include anti-rattler portions which project outwardly and laterally with respect to said surfaces for sliding coaction within the guide channels.
